STALL TYPE RACK

George Robert Johnson, Milford, Conn.

Application August 13, 1952, Serial No. 304,095

1 Claim. (Cl. 214—16.4)

The present invention relates to stall type racks and particularly to such type racks for storing heavy objects.

Heretofore in storing strip or rod steel, for example, which is moved in bundles by means of a crane or similar lift, it has been impossible to deposit the same directly in the stall due to the interference of the stall with the crane or lift. Accordingly, it has been necessary to deposit the steel adjacent the rack and hand fill the rack. This is a laborious and time-consuming job and one which increases substantially the cost of storing such steel.

The present invention overcomes these difficulties by providing a stall type rack with a slidable section which may be withdrawn from the stall to an exposed position in which the rod or strip steel may be deposited directly by the crane, after which the slidable section may be returned to the stall to storage position.

A feature of the invention resides in providing roller supports for the slidable section which aid in its movement and which are so arranged in the rack as to be pitched to the rear thereof so as to prevent inadvertent shifting of the slidable section out of the stall.

Another feature of the invention is the provision of a novel supporting means for the free end of the slidable section for supporting the same when drawn outwardly to exposed position and for supporting the slidable section when the load is applied thereto. In the preferred form of the invention the support is adjustable so that it may cooperate with the slidable section for any stall in the rack.

Another feature of the invention resides in the load supporting portions in the slidable member for supporting bundles of rods or strips in a position therein to permit the ready removal of the chains or other lifting means from around the bundle after they have been deposited within the slidable section.

The rack according to the preferred form of the invention is fabricated from channel and angle iron and can be readily made up in any desired number of stalls as may be required. This material also lends to simplicity and cheapness in manufacture of the same.

Other features and advantages of the invention will be apparent from the specification and claim when considered in connection with the drawings in which:

Figure 1 shows a side view of the rack.

Fig. 2 shows a front end view of the rack.

Fig. 3 shows a detailed view partly in section of the rack, with the slidable section in place.

Fig. 4 shows a detailed sectional view of the roller.

Fig. 5 shows a detailed exploded view of the interconnecting means between the carriage and slidable section.

As shown in the drawing, the present invention relates to stall type racks which can be fabricated from I-beams, channel and angle iron to the required shape to produce horizontally extending open-ended stalls. While the stalls may be arranged in side by side relation either horizontally or vertically or in both directions as required, they are herein illustrated as being superposed in a vertical direction.

2

This is accomplished by a plurality of I-beams 10 which have transverse channel members 11 connected thereto to provide the sides for the rack which are connected by transversely extending channel 13 to form the rack provided with superposed stalls adapted for the storage of heavy elongate articles such as bundles of steel rods or strips or other similar material which require article lifting means, such as a crane or lift truck, not shown, for moving the material.

5 10 With stall type racks it is impossible to load the rack by article lifting means which usually raise the material by providing slings or the like article supporting members which extend under the article.

According to the present this difficulty is overcome by 15 providing each stall with a slidable section 14. In the illustrated form of the invention the slidable section comprises angle irons 15 connected by U-shaped members 16 formed of channel iron. The U-shaped members are nested in and connected to the angle irons, as shown in 20 Fig. 3, with the bow 16a of the U extending between the angle irons and forming therewith the bottom or base of the slidable section and the legs 16b of the U extending upwardly and each forming a part of the side wall for an open-top slidable section. The side walls so formed will 25 have openings therein which will enable the lifting means to deposit the bundles of steel directly into the section as will be described.

While the slidable section may be mounted in the stall for sliding movement in any suitable manner, in the 30 herein illustrated form of the invention rollers 17 are provided and mounted by antifriction bearings 18 on a plurality of rods 19 extending between the sides of the rack, as shown in Figs. 3 and 4, to support the sections in each stall to facilitate sliding of the sections into and out of the stall.

35 In the preferred form of the invention the rods are so arranged, as shown in Fig. 1, that the plane of the rollers is slightly inclined to the rear so that the slidable section tends to move into position within the stall by gravity. This is particularly true when a load is placed in the stall. The pitch of the incline is slight, however, being approximately one-quarter of an inch in six feet, which is exaggerated in the drawing in order to illustrate the feature and will not interfere with intentional movement thereof 40 into projected position. At the rear end of each stall there is provided a transverse member 20 which engages the back end of the slidable member and forms a stop therefor.

In accordance with the present invention novel means 50 are provided for supporting the front end of each slidable section when in projected position. In the illustrated form of the invention this means comprises a wheeled carriage 21 having thereon means 22 for interlocking with the front end of the selected slidable section to be projected and to support the front end in all projected positions. Preferably the carriage comprises the usual lift truck 23 of the type used for lifting material storing pallets and having a jack means 24 thereon for raising the platform 23a of the carriage in response to operation 55 of the handle 25. Supported on the platform is a vertically extensible member 26 adapted to be adjusted to a position to engage and support the selected slidable section. While this member may be any type of mechanical or hydraulic jack, for the purpose of simplicity it is herein illustrated as manually operable telescopic members 27, 28 movable to a position in which the means 22 is aligned with the front of the selected slidable section and held in adjustment by a pin 29 passing through both 60 of the telescopic members.

65 70 The supporting member, in accordance with the present invention, is detachably connected to any one of the selected slidable members. For this purpose each of the

slidable members has an outwardly facing U clip 30 secured to the front end thereof and the support has a tongue 31 mounted thereon in line with the slide for the bottom stall and a tongue 31a on the end of the upper extensible member 28. The tongue and the U clip are provided with pairs of spaced holes 32 which are adapted to be aligned when the tongue is positioned in the U clip and pins 33 are inserted through the holes to hold the front of the slideable section to the support against pivotal action. While the pins 33 may be separate pins they are herein shown as connected.

In carrying out the present invention I have found it advantageous, particularly where bundles of material are handled, to provide bundle engaging means 34 to receive and support the bundle. This means is herein illustrated as comprising triangular blocks 35 mounted in the channel of members 16 and having angular surfaces 35a positioned to engage and support a bundle 36 out of contact with the sides and bottom of the base so that after the bundle has been inserted through the open top of the slideable section the lifting slings or members 37 can be withdrawn readily from under the bundle.

In operation the stall in which it is desired to store the bundle of steel is selected and the carriage moved into position in front of the stall. The extensible member on the carriage is adjusted if necessary so that the carriage may be connected to the front end of the selected slideable section. The carriage is then withdrawn causing the slideable section to be projected from within its stall for substantially its full length wherein the open top will be in exposed position. In this position the front roller of the stall will support the rear end of the section and the carriage will support the front end of the section. The bundle of steel is then moved by the lifting means through the open top and into position in which it is supported by the blocks 35. Because of the open spaces in the sides of the slideable section the lifting means can readily deposit the bundle into proper position in the slideable section without any interference. After the load has been placed in position the slings or other lift means, which are disposed between the bundle-supporting means, can be readily withdrawn without interference by the slideable section. The section is then returned to the stall and the carriage disconnected therefrom.

The present invention enables bundles of steel to be stored directly into stall racks without the necessity of placing the steel in the stall piece by piece as is the present method. This effects economy both as to time and manpower in storing quantities of steel.

Inasmuch as the stalls are formed by fabricating channel and I-beams, they may be readily fabricated in any desired size or shape as may be required without in any way deviating from the invention so that great quantities of steel may be readily and quickly stored.

While the present invention has been described as handling bundles of steel, it is equally applicable to the storing of other heavy objects which must be inserted into the top of the slideable section by lifting means.

Variations and modifications may be made within the scope of the claim and portions of the improvements may be used without others.

I claim:

10 In a stall type rack having vertical and transverse members interconnected to provide a plurality of superposed horizontally disposed open-ended stalls for storing heavy objects movable by article lifting means, the improvement which comprises providing a slideable section in each stall, said section including a base and side members with the 15 side members having spaces therein forming an open-top unit adapted when in receiving position to receive the object to be stored and the spaces in the sides permitting the lifting means to deposit the object on the base without interference; stop means at the rear of each stall to engage the section and prevent movement of the section therethrough; means mounting said slideable sections for movement through the front open end of the stall for substantially the full length of the section to present the open top of a selected slideable section to receive heavy objects 20 deposited directly by article lifting means, said means including a plurality of longitudinally spaced, transversely extending, elongate, ball bearing supported rollers in each stall extending thereacross and having their axes lying in a rearwardly inclined plane whereby the sections are urged 25 rearwardly to said stop means and against unintentional movement through the front of the stall; and a movable carriage having a vertically extensible support post thereon, said post having means at the upper end to interlock with the selected section and support the front end of the 30 slideable section in all projected positions.
